 and Albert Boren

Application April 27, 1934, Serial No. 722,611

5 Claims. (Cl. 225—18)

This invention relates to improvements in beverage dispensing devices of the type in which carbon dioxide ice is utilized for obtaining carbon dioxide gas for dispensing and cooling purposes. 5 One object of the invention is to provide a beverage dispensing device in the form of a relatively small compact unit suitable for operative attachment to a beverage container.

Another object is to provide a unit, apparatus 10 or machine of the type set forth especially adapted for use in combination with standard beer kegs or containers.

Still another object is to provide such a device 15 including certain improved measures for safe operation. Other objects will appear as this specification proceeds.

Accordingly the invention is embodied in a beverage dispensing device arranged and constructed as hereinafter set forth and as illustrated in the accompanying drawings in which

Fig. 1 is a top plan view of the device.

Fig. 2 is a horizontal sectional view of the device taken on the line 2—2 of Figure 3.

Fig. 3 is a side view of the device looking in the direction of arrow 3 in Figure 1 with parts in section and parts broken away, showing the device mounted in operative relation to a keg of beer and enclosed within an outer container.

It is proposed to use carbon dioxide ice for dispensing and cooling purposes. Such ice is sold commercially in the form of bricks. The device therefore includes as a main element an ice box 4 in a form and of dimensions such as will conveniently contain a piece of carbon dioxide ice of a standard size. The ice box also serves as a supporting body for the other elements of the device. The box is made of metal and sufficiently strong to withstand the pressure of the carbon dioxide gas resulting from the natural sublimation of the ice. The box is closed pressure tight by any suitable means such as a cover 5 clamped on tight by a clamp 6 and screw 7, a gasket 8 being provided for tight closure, see Figure 3.

The ice box is provided with a suitable pressure 45 gage 9 for registering the pressure within the box. The numeral 10 denotes a bleeder valve and 11 is a safety valve, both communicating with the interior of the ice box. The bleeder valve is constructed similar to the bleeder valve 12, see Figure 2. The valve comprises a valve body 13 adapted to be attached by screwing it into the ice box. Inside the valve body there is a needle valve 14 seated under pressure of a spring 15 to close the opening 16 in the valve. A screw cap 17 closes the valve and affords means for varying

the tension of the spring 15 to adjust or set the valve for a predetermined pressure.

The safety valve 11, see Figure 3, comprises a valve body adapted to be attached by screwing it on to the ice box. The valve body is hollow and communicates with the interior of the ice box. 18 is a membrane of suitable material which closes the upper end of the valve and is held in place by an open cap 19. The membrane is so designed that when a given excessive pressure exists within the ice box, the membrane will blow out and permit the escape of the gas.

On top of the ice box there is mounted a reducing valve unit 20 having a leg 21 secured to the ice box by screws 23. The reducing valve 15 body 24 forms a valve chamber 25 having an inlet 26, Figure 3, in the aforesaid leg 21. The inlet 26 leads into the ice box chamber 27. The valve has an outlet at 28. There is a vertical passage 29 within the leg 21 from the inlet 26 which communicates at the top with a horizontal passage 30 which through a boss 31 leads into the valve chamber, see Figure 2.

The inlet passage 29 is closed at the top by an adjustable valve 32, the valve passage in turn 25 being closed by an outside cap. The inner end of the horizontal passage 30 has screwed into it an apertured valve seat nipple 33 the aperture 34 of which is closed by a needle valve 35 adjustably supported in a boss 36. The latter forms the one 30 end of a floating yoke 37 within the valve chamber. The other end of said yoke forms a flange 38 and between the flange and the valve body there is mounted a bellows diaphragm 39.

The yoke 37 is held in position by the boss 35 36 which slides in the valve cover 40 and a spring 41 tends to force the yoke in one direction to cause the needle valve 35 to close the passage 34. The tension of the spring is regulated by a screw 42. The other end of the yoke is held in position 40 by the diaphragm and a spring 44 which bears against the yoke and is adjustably held by a screw 43 in the dome cap 45 which closes the other end of the valve chamber.

It will be seen therefore that carbon dioxide 45 gas resulting from the sublimation within the ice box passes upward through the passage 29 and then into the valve chamber through the passage 30. The flow of gas is controlled first by the valve 32 and secondly by the operation of the needle valve 35. The reduction in pressure may be controlled to a very fine point by adjusting the two opposed springs 41 and 44 in combination with the diaphragm. An incoming excess of pressure 50 55

acts against the diaphragm 39 to close the needle valve.

Into the valve until 20 there is screwed a cross connection 47 which has four openings or passages. One branch 48 leads to the valve chamber outlet 28. Another, directly opposite, leads to the bleeder valve 12. A third branch 49 connects with a gage 50 and the fourth branch 51 leads to a flexible hose 52. To the other end of the latter 10 there is secured a standard coupling 53, Figure 3, which forms the male member of a standard valve, the female member 55 of which is permanently mounted in the beverage container in this case a beer keg 56. The coupling or male number 53 has a handle 57 for operatively connecting the female and male members of the standard valve. The coupling may also contain a check valve 60 of conventional construction. If the coupling as such does not contain a check valve, 20 the latter may be inserted at some other point in the flexible hose between the reducing valve unit and the beverage containers.

The standard valve members 53 and 55 are illustrated conventionally, because such standard 25 valves may be purchased in the open market under various trade names. The numeral 65 denotes an outer container having a cover 66. The beer keg and the dispensing unit are placed inside the outer container. In the present instance 30 the dispensing unit is shown resting directly on the beer keg. It may of course rest on some support other than the keg. Suitable insulation may be wrapped around the ice box and the outer container may also be insulated on the inside. 35 Such insulation is not illustrated as it forms no part of this invention.

The operation is as follows. A piece of carbon dioxide ice is placed within the ice box which is closed gas tight and the bleeder valve 10 is adjusted to regulate the pressure within the ice box 40 and which may be observed on the gage 9. The reducing valve elements having been set to reduce the pressure to the desired degree, it will be seen that the gas then passes from the ice box into the reducing valve and then at a reduced 45 pressure into the rubber hose and thence into the beverage container.

The reduced gas pressure is of course observable on the gage 50 and the bleeder valve 12 will be 50 set at the reduced pressure degree or perhaps slightly higher to insure that gas at no more than the desired low pressure passes into the beverage container.

It will therefore be observed that the bleeder 55 valve 10 controls the pressure within the ice box, the reducing valve unit controls the reduction of pressure. The other bleeder valve 12 controls the pressure of the gas as it passes into the beverage container and the check valve 60 prevents the 60 passage of high pressure gas from the container to the reducing valve unit if such should occur. So long as the pressure in the apparatus remains at the desired low degree gas will pass through the check valve 60 into the beverage container.

It is well known in the art that beer is a difficult beverage to deal with in respect to temperature and dispensing and that great care is required to properly dispense beer. The apparatus herein disclosed has been tested and found 70 to function as intended. The carbon dioxide gas may be controlled to a fine point in the reducing valve and perfect safety and control is obtained by means of the bleeder valves and the safety valve. In addition, of course, both the pressure 75 within the ice box as well as the temperature

within the outer container are controlled by the bleeder valve 10.

The apparatus herein disclosed is compact in form and economic to manufacture and operate. The device may of course be placed upon or near the beverage container in any suitable position other than that illustrated. It will also be understood that changes and alterations in the details and in the arrangement of parts may be made without departing from the scope of the 10 appended claims.

I claim:

1. A beverage cooling and dispensing apparatus comprising a closed refrigerant chamber for the reception of solid carbon dioxide, means acting 15 to prevent the pressure of the gaseous carbon dioxide liberated by the evaporation of the solid carbon dioxide in said chamber from going beyond a predetermined point, a valve housing in close proximity and adjacent to said chamber, a 20 conduit communicating between said chamber and said housing, a valve mechanism in said housing for reducing the gaseous carbon dioxide admitted thereto to another predetermined pressure, means acting to prevent the pressure of the 25 gaseous carbon dioxide being discharged from said housing from going beyond the predetermined point at which it is emitted from said housing, and a second conduit in communication with said housing for conveying the gas under 30 said last-named pressure to a receptacle containing the beverage to be cooled and placed under the desired head of pressure for discharge through a dispensing faucet, whereby the gaseous carbon dioxide passes from said chamber under a 35 predetermined pressure through said first-named conduit to said housing to be reduced therein to another predetermined pressure and from said housing at such predetermined reduced pressure through said second-named conduit for introduction into the beverage containing receptacle to cause the beverage to be cooled and discharged 40 upon the opening of the dispensing faucet.

2. A beverage cooling and dispensing apparatus comprising a closed refrigerant chamber for the 45 reception of solid carbon dioxide, means acting to prevent the pressure of the gaseous carbon dioxide liberated by the evaporation of the solid carbon dioxide in said chamber from going beyond a predetermined point, a valve housing in close 50 proximity and adjacent to said chamber, a conduit communicating between said chamber and said housing, a valve mechanism in said housing for reducing the gaseous carbon dioxide admitted thereto to another predetermined pressure, means 55 acting to prevent the pressure of the gaseous carbon dioxide being discharged from said housing from going beyond the predetermined point at which it is emitted from said housing, a second 60 conduit in communication with said housing for conveying the gas under said last-named pressure to a receptacle containing the beverage to be cooled and placed under the desired head of pressure for discharge through a dispensing faucet, 65 and means in said second conduit for permitting the flow of gas therethrough in only one direction whereby the gaseous carbon dioxide passes from said chamber under a predetermined pressure through said first-named conduit to said housing 70 to be reduced therein to another predetermined pressure and from said housing at such predetermined reduced pressure through said second-named conduit for introduction into the beverage containing receptacle to cause the beverage to be 75

cooled and discharged upon the opening of the dispensing faucet.

3. A beverage cooling and dispensing apparatus comprising a closed refrigerant chamber for the reception of solid carbon dioxide, means acting to prevent the pressure of the gaseous carbon dioxide liberated by the evaporation of the solid carbon dioxide in said chamber from going beyond a predetermined point, a valve housing in close proximity and adjacent to said chamber, a conduit communicating between said chamber and said housing, a valve mechanism in said housing for reducing the gaseous carbon dioxide admitted thereto to another predetermined pressure, means associated with said valve mechanism for regulating the pressure to which the gaseous carbon dioxide is to be reduced, means acting to prevent the pressure of the gaseous carbon dioxide being discharged from said housing from going beyond the predetermined point at which it is emitted from said housing, a second conduit in communication with said housing for conveying the gas under said last-named pressure to a receptacle containing the beverage to be cooled and placed under the desired head of pressure for discharge through a dispensing faucet, and means in said second conduit for permitting the flow of gas therethrough in only one direction whereby the gaseous carbon dioxide passes from said chamber under a predetermined pressure through said first-named conduit to said housing to be reduced therein to another predetermined pressure and from said housing at such predetermined reduced pressure through said second-named conduit for introduction into the beverage containing receptacle to cause the beverage to be cooled and discharged upon the opening of the dispensing faucet.
4. A beverage cooling and dispensing apparatus comprising a closed refrigerant chamber for the reception of solid carbon dioxide, means acting to prevent the pressure of the gaseous carbon dioxide liberated by the evaporation of the solid carbon dioxide in said chamber from going beyond a predetermined point, a valve housing in close proximity and adjacent to said chamber, said housing having an inlet provided with means for controlling the flow of gaseous carbon dioxide therethrough, a conduit communicating between said chamber and said housing, a valve mechanism in said housing for reducing the gaseous carbon dioxide admitted thereto to another predetermined pressure, an outlet in said housing for the discharge of the gaseous carbon dioxide after being reduced to such predetermined pressure, means associated with said valve mechanism for regulating the pressure to which the gaseous carbon dioxide is to be reduced, means acting to prevent the pressure of the gaseous carbon dioxide being discharged from said housing from going beyond the predetermined point at which it is emitted from said housing, a second conduit in communication with said housing for conveying the gas under said last-named pressure to a receptacle containing the beverage to be cooled and placed under the desired head of pressure for discharge through a dispensing faucet, and means in said second conduit for permitting the flow of gas therethrough in only one direction whereby the gaseous carbon dioxide passes from said chamber under a predetermined pressure through said first-named conduit to said housing to be reduced therein to another predetermined pressure and from said housing at such predetermined reduced pressure through said second-named conduit for introduction into the beverage containing receptacle to cause the beverage to be cooled and discharged upon the opening of the dispensing faucet.

from going beyond the predetermined point at which it is emitted from said housing, and a second conduit in communication with said housing for conveying the gas under said last-named pressure to a receptacle containing the beverage to be cooled and placed under the desired head of pressure for discharge through a dispensing faucet, whereby the gaseous carbon dioxide passes from said chamber under a predetermined pressure through said first-named conduit to said housing to be reduced therein to another predetermined pressure and from said housing at such predetermined reduced pressure through said second-named conduit for introduction into the beverage containing receptacle to cause the beverage to be cooled and discharged upon the opening of the dispensing faucet.

5. A beverage cooling and dispensing apparatus comprising a closed refrigerant chamber for the reception of solid carbon dioxide, means acting to prevent the pressure of the gaseous carbon dioxide liberated by the evaporation of the solid carbon dioxide in said chamber from going beyond a predetermined point, a valve housing in close proximity and adjacent to said chamber, said housing having an inlet provided with means for controlling the flow of gaseous carbon dioxide therethrough, a conduit communicating between said chamber and said housing, a valve mechanism in said housing for reducing the gaseous carbon dioxide admitted thereto to another predetermined pressure, an outlet in said housing for the discharge of the gaseous carbon dioxide after being reduced to such predetermined pressure, means associated with said valve mechanism for regulating the pressure to which the gaseous carbon dioxide is to be reduced, means acting to prevent the pressure of the gaseous carbon dioxide being discharged from said housing from going beyond the predetermined point at which it is emitted from said housing, a second conduit in communication with said housing for conveying the gas under said last-named pressure to a receptacle containing the beverage to be cooled and placed under the desired head of pressure for discharge through a dispensing faucet, and means in said second conduit for permitting the flow of gas therethrough in only one direction whereby the gaseous carbon dioxide passes from said chamber under a predetermined pressure through said first-named conduit to said housing to be reduced therein to another predetermined pressure and from said housing at such predetermined reduced pressure through said second-named conduit for introduction into the beverage containing receptacle to cause the beverage to be cooled and discharged upon the opening of the dispensing faucet.
